UNITED STATES PATENT OFFICE

HARRY C. SCHICK, OF MADISON, NEW JERSEY

DESIGN FOR A NECKLACE CLASP

Application filed April 7, 1930. Serial No. 35,180. Term of patent 3½ years.

To all whom it may concern:

Be it known that I, HARRY C. SCHICK, a citizen of the United States, residing at Madison, in the county of Morris and State of New Jersey, have invented a new, original, and ornamental Design for Necklace Clasp, of which the following is a specification, reference being had to the accompanying drawings, forming part thereof.

In said drawings, Fig. 1 is a top face or

plan view, Fig. 2 is a side elevation, and Fig. 3 is a fragmentary face view on an enlarged scale, of a necklace clasp, showing my new design.

I claim:—

The ornamental design for a necklace clasp, as shown.

Dated this 3rd day of April, 1930.

HARRY C. SCHICK.
